(No Model.)

C. C. E. VAN ALSTINE.
THREAD TWISTER.

No. 578,792.

Patented Mar. 16, 1897.

WITNESSES:

INVENTOR:

Cornelius Charles Edgar Van Alstine

BY Gartners & Co. ATTY'S.

UNITED STATES PATENT OFFICE.

CORNELIUS CHARLES EDGAR VAN ALSTINE, OF PATERSON, NEW JERSEY,
ASSIGNOR OF ONE-HALF TO GEORGE WASHINGTON GRAHAM, OF SAME
PLACE.

THREAD-TWISTER.

SPECIFICATION forming part of Letters Patent No. 578,792, dated March 16, 1897.

Application filed September 12, 1896. Serial No. 605,620. (No model.)

To all whom it may concern:

Be it known that I, CORNELIUS CHARLES EDGAR VAN ALSTINE, a citizen of the United States, residing in Paterson, county of Passaic, 5 and State of New Jersey, have invented certain new and useful Improvements in Thread-Twisters; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of my present invention is to provide a doubler with means for twisting the threads to furnish a finished product, and thus avoid the necessity of subjecting the threads to the process of throwing, of simple, 20 strong, and durable construction, reliable and efficient in operation.

The invention consists in the improved doubler and its twisting means, and in the combination and arrangement of the various parts 25 thereof, substantially as will be hereinafter more fully described, and finally embodied in the clauses of the claim.

In the accompanying drawings, Figure 1 represents an end elevation of a doubler of 30 ordinary construction provided with my improvements, only those parts of the doubler being shown which are necessary to clearly illustrate the nature of my said invention; Fig. 2, an enlarged detail end elevation of 35 the right-hand upper portion of Fig. 1; Fig. 3, a detail front elevation of Fig. 2, with certain portions removed and others broken away. Figs. 4 and 5 are a front elevation and top plan view, respectively, of the twister 40 and its supporting reciprocating bar; Fig. 6, an enlarged perspective view of the twister or spinner proper, and Fig. 7 a side elevation thereof.

In said drawings, *a* represents the frame, 45 in which are arranged—and on each side of the center thereof—the shafts *b* and *b'*, operated in the usual manner, (the driving mechanism therefor not being shown.) On each of said shafts is mounted a pinion *b'*, meshing into gear-wheel *b*, which latter is arranged 50 on the shaft *c*, carrying the cam-wheel *c'*, by

means of which the antifriction-rollers *c* are adapted to be operated. The roller *c* is arranged on the vertical lever *c'*, fulcrumed at its lower end, as at *c*, to the frame of the 55 machine. The upper end of said lever is connected by means of the rod *h* to the reciprocating bar *h*. On the shaft *b* are mounted at certain intervals a series of friction-wheels *d*, engaging the friction-rollers *d'*, which are 60 arranged on a series of short shafts or spindles *d*, supported in the brackets *d*, arranged at right angles to the shaft *d* and secured to the frame *a* in any desired manner. On each of said shafts or spindles *d* is secured a toothed 65 or ratchet wheel *f*, adapted to be engaged by the pawl-shaped end of the lever *f'*, pivoted, as at *f*, to a projection of the bracket-frame *a* in a manner hereinafter described.

On each of the shafts *d* and between the friction-rollers *d'* is arranged a bobbin or spool *e* of the usual and well-known construction.

On the reciprocating bar *h*, which is provided at certain intervals (to correspond to the number of bobbins) with recesses *h*, are 75 secured a series of bracket-plates *h* by means of the screws *h* and *h*, respectively, the latter ones penetrating elongated radial slots *h*, arranged in their respective bracket-plates. Each of said bracket-plates *h* is provided with 80 a central groove or recess *h*, in which the grooved pulley *h* is free to revolve, which pulley is mounted on the hollow shaft *h*, having its bearings in the said bracket-plate and also in the cover *h* of the latter. Said shaft *h* 85 penetrates the recess *h* of the reciprocating bar *h* and projects beyond its rear surface. The pulley *h* rests in operative position on an endless belt *i*, passing over the horizontally-arranged grooved pulleys *i*, operated 90 from the main driving-shaft in any desired manner.

The bracket-plate *h* is provided at its slotted end with a notch *h*, engaged by the flat spring *h*, which latter tends to force the said plate against the projection *h* of the lever *h*, pivoted, as at *h*, and controlled by the flat spring *h*, all as clearly shown in Figs. 4 and 5 of the drawings. When the pulley *h* is to be thrown out of engagement with the 100 endless belt *i*, the lever *h* is pressed backward by the operator, and after the bracket-

plate h^6 has been swung upward on the screw h^{12} (serving as a fulcrum) by the action of spring h^{14} the said lever h^{15} is released, when its projection h^{17} engages the slot h^{10} and thus holds the bracket-plate and the pulley carried thereby out of operative position.

The hollow shaft h^7 and its pulley h^8 are provided at one side with the open slots m^3 and m^2 , respectively, of a size large enough to admit the insertion of the threads to be twisted. Said slots are capable of being brought in alinement with the slots m' and m^{11} , arranged in and penetrating one side of the bracket-plate h^6 and its cover h^9 , respectively. On the forward end of the shaft h^8 is arranged a wire forming a loop m , which loop stands substantially in the center line of the hollow shaft and at right angles thereto. On the opposite end of said shaft h^8 is also arranged a wire forming a loop m^{10} , which latter is substantially in the center line of said shaft and in alinement therewith.

By preference the hollow shaft h^7 is lined with porcelain or any other suitable material to prevent the threads, while passing through, from becoming bruised or otherwise impaired. The threads $t' t'$ to be twisted pass from the bobbins $u' u'$ (which latter are arranged on the bracket-frame a' in the usual manner) over the rod t^3 , through loop g' , and over rod t^3 , into and through the loop m , thence through the hollow shaft h^7 , loop m^{10} , onto the bobbin e . The rods $t' t'$ are supported in the bracket-frames a^3 , while the loop g' is carried by the spring-wire g , which latter is arranged in such a manner that when the thread passing through its respective loop g' breaks it will drop down upon the lever f' and thus throw the latter into engagement with one of the notches of the toothed wheel f and thus stop the rotation of the same and the shaft and bobbin connected therewith.

As the hollow shaft h^7 , carrying the loop m , (at right angles to the center line of said shaft,) is revolved the threads upon passing through said loop m are twisted together and in that form are wound upon the bobbin. When the twister is to be threaded, the slots m^3 and m^2 of the shaft h^7 and pulley h^8 are brought in alinement with the slots m' and m^{11} of the bracket-plate h^6 and h^9 , respectively, as will be manifest.

I do not intend to limit myself to the precise construction shown and described, as various alterations can be made without changing the scope of my invention; but

What I claim as new, and desire to secure by Letters Patent, is—

1. A twister or spinner, consisting of a frame, a hollow slotted shaft in said frame, a loop on one end of said shaft and arranged at right angles to the center line thereof, means on the end of the shaft for guiding the yarn clear of the slot and means for revolving said shaft, all said parts, substantially as and for the purposes described.

2. A twister or spinner, consisting of a frame, a hollow slotted shaft in said frame, a loop on one end of said shaft and at right angles thereto, a loop on the other end of the shaft and in alinement with the center line thereof, and means for revolving said shaft, all said parts, substantially as and for the purposes described.

3. A twister or spinner, consisting of a frame, a hollow shaft in said frame and provided with an elongated slot, a grooved pulley mounted on said shaft and also provided with a slot communicating and in alinement with the slot of the hollow shaft, a loop at one end of the shaft and at right angles thereto, and means for operating the pulley, all said parts, substantially as and for the purposes described.

4. A twister or spinner, consisting of a frame, a hollow shaft in said frame and provided with an elongated slot, a grooved pulley mounted on said shaft and also provided with a slot communicating and in alinement with the slot in the hollow shaft, a loop arranged at one end of the shaft and at right angles to the center line thereof, a loop centrally arranged on the other end of the shaft and in alinement therewith, and means for operating the pulley, all said parts, substantially as and for the purposes described.

5. A twister or spinner, consisting of a frame provided at one side thereof with a slot, a hollow shaft arranged in said frame, a pulley on said shaft, said pulley and shaft being provided on one side with an open slot, capable of being brought in alinement with the slot in the frame, a loop arranged on one end of the shaft and at right angles to the center line thereof, a loop on the other end of the shaft and in alinement therewith, and means for operating the pulley, all said parts, substantially as and for the purposes described.

6. The combination with the reciprocating bar of a doubler, a bracket-plate adjustably arranged on said bar, means for locking said bracket-plate in its adjusted positions, a hollow shaft arranged in said bracket-plate, a loop on one end of the shaft and at right angles thereto, and means for revolving said shaft, all said parts, substantially as and for the purposes described.

7. The combination with a bar, of a bracket-plate arranged on and pivoted with one end to said bar and provided at its other end with an elongated slot, a spring controlling said bracket-plate, a pivoted lever adapted to lock said plate against the action of the spring when in normal position, and to engage the slot of said bracket when out of normal position, a hollow shaft arranged in said bracket-plate, a loop on one end of said shaft and at right angles thereto, and means for revolving the shaft, all said parts, substantially as and for the purposes described.

8. The combination with a bar, of a bracket-plate arranged on and pivoted with one end

to said bar and provided at its other end with an elongated slot, a spring controlling said bracket-plate, a pivoted lever adapted to lock said plate against the action of the spring when in normal position and to engage the slot of said bracket-plate when out of normal position, a hollow shaft arranged in said bracket-plate, a loop on one end of said shaft and at right angles thereto, a loop at the other end of the shaft and in alinement with the center line thereof, and means for revolving the shaft, all said parts, substantially as and for the purposes described.

9. The combination with a bar, of a bracket-plate arranged on said bar and provided at one side with a transverse open slot penetrating said bracket to about its center, a hollow shaft arranged in said bracket-plate, a pulley on said shaft, said pulley and shaft being provided at one side with an open slot, adapted to be brought in alinement with the transverse slot of the bracket-plate, a loop on one end of said shaft and at right angles thereto, and means for revolving the pulley, all said

parts, substantially as and for the purposes 25 described.

10. The combination with a bar, of a bracket-plate arranged on said bar and provided at one side with a transverse open slot penetrating said bracket to about its center, a hollow 30 shaft arranged in said bracket-plate, a pulley on said shaft, said pulley and shaft being provided at one side with an open slot, adapted to be brought in alinement with the transverse slot of the bracket-plate, a loop on one 35 end of said shaft and at right angles thereto, a loop at the other end of the shaft and in alinement with the center line thereof, and means for revolving the pulley, all said parts, substantially as and for the purposes 40 described.

In testimony that I claim the foregoing I have hereunto set my hand this 4th day of September, 1896.

CORNELIUS CHARLES EDGAR VAN ALSTINE.
